UNITED STATES PATENT OFFICE.

ROBERT FUST, OF GLOGAU, GERMANY.

ARRANGEMENT FOR REMOVING SECRETIONS FROM DENTAL CANALS BY SUCTION.

Application filed August 30, 1923, Serial No. 660,214, and in Germany January 31, 1923.

This invention relates to dental appliances, and more particularly to an arrangement for sucking off secretions which may have collected in dental canals. The main object of the invention is to provide improved means which will enable the dentist to effectively maintain a vacuum within the socket of the tooth, or the ulceration therebehind, for as long as possible a duration without the application of hurtful pressure upon the affected tooth.

Another object of the invention is to provide a device which, once applied, may be left without attendance, so that the dentist may have both his hands free for other work.

A further object of the invention is the provision of a device of the said kind which will not molest the patient and which, besides, will not be disarranged by slight movements of the patient's head.

With these and other objects in view the invention broadly consists in a suction arrangement of which the nozzle or suction piece proper, hereinafter called the "mouthpiece," is held to the tooth by means of a clamp or clip; means being provided to so securely hold the said mouthpiece in airtight connection with the tooth as to prevent its becoming deranged by slight movements of the patient's head.

The invention is illustrated in the accompanying drawings illustrating several modifications by way of example.

Fig. 1 shows the general arrangement of the appliance in part sectional side elevation, the mouthpiece in this example being in the shape of a spring clip.

Figs. 2 and 3 are front and side elevation, the latter partly in section, of an arrangement in which the mouthpiece is held to the tooth by means of a yoke or stirrup.

Figs. 4 and 5 are similar views of a slightly modified arrangement.

Fig. 6 is a section through a screw threaded mouthpiece adapted to be screwed into a drill hole in the tooth.

Fig. 7 is a section through a similar device having a suction plate of slightly modified form to the one shown in Fig. 8.

Figs. 8 and 9 illustrate a modification of the screw-threaded mouth-piece and suction plate in sectional elevation and plan view respectively, whilst Fig. 8^a shows the suction plate in perspective view.

Figs. 10, 10^a and 10^b are similar views

of still another modification, especially of the suction plate.

Referring to Fig. 1, the upper jaw is denoted by the figure 1, 2 is the ulceration to be cleared, 3 the root of the tooth with its dental canal 4 extending right into the crown. 4' is a drill hole made by the dentist preparatory to removing the secretions, and extending from the outer enamel into the tooth socket. The appliance used to remove the secretions consists of a clip 6 having resilient legs 5 arranged to pivot on a pin 7 and adapted to be clamped to the tooth as shown in the figure. The said clip is enclosed by a piece of India rubber tube 8, which makes an airtight joint upon the tooth above the drill hole 4'. To the said rubber tube 8 is attached another tube, preferably made of glass, whilst a spiral spring 9 is inserted into the rubber tubing above the glass tube to impart to the former a greater resistance to the pressure of the outer air during the suction operation.

With its lower end the glass tube 10 is passed through a stopper 11 into a glass vessel 12. Another glass tube 13 adjacent to the glass tube 10 is passed through the same stopper 11 and, with its outer end, is in connection with an india-rubber bulb 15 by means of a length of rubber tubing 14 with inserted spiral spring as in the case of the tube 8 just referred to. Bulb 15 also is provided with a coil spring 8^a to render it more resistable to the pressure of the outer air. A pressure imparted to the said bulb will first of all force air from within the bulb through the valve 16 to the outside, so that after the release of the bulb and consequent closing of the valve a partial vacuum will be formed, which produces a sucking effect and causes matter from the ulceration 2 to pass through the dental canal 4, drill hole 4' and glass tube 10 into the collector 12.

It is evident that the arrangement just referred to permits of the vacuum, or partial vacuum, being maintained without any pressure being applied to the affected tooth, and without moderate movements of the patient's head being able to disturb the airtight connection between the ulceration and the collecting means. The dentist, therefor, need not attend to the attachment in any way once the same is applied but may have both his hands free for other manipulations.

In the arrangement according to Figs. 2

and 3, the tooth to be treated is denominated 3, while 4 is the tooth socket and 4' the drill hole as in the foregoing example. The suction conduit comprises the india rubber tube 8 with its inserted coil spring, and communication between this tube and the tooth socket is established by means of a screw threaded mouth piece 17, preferably made of iron and arranged to be screwed up and down within the yoke or stirrup 19, which, for this purpose, is provided with a corresponding screw thread at its centre. At its lower end the said mouthpiece terminates into a loose section of suction tube 21, attached to the mouth piece 17 by means of a ball socket joint 20. The purpose of this loose piece of tubing is to enable a better insertion of the appliance into the hole 4' made by the dentist.

20 In order to provide an airtight joint with the tooth, the tube 21 is provided with a flat suction pad 22 made of india rubber or the like material, and which is pressed tightly upon the tooth when the mouth piece 17 is screwed down in the stirrup 19. Fixing the stirrup upon the crown of the tooth is effected by means of clips without the tooth being pressed thereby in the direction of its root. The said clips are pivoted to the stirrup at 23 and are adapted, with their jaws 24, to bear sideways upon the tooth by means of the set screws 28 having preferably milled heads 27. The stirrup 19, in this way, forms a support for the mouthpiece 17 while the latter is being pressed onto the tooth; the pressure being directly taken up by the jaws 24; it is not transmitted to the root of the tooth or to the patient's jaw.

40 The modification shown in Figs. 4 and 5 differs from the aforesaid only in that the fixing jaws 24 are provided with pads 23 for the purpose of preventing the tooth being clamped by the metallic parts of the appliance.

45 In the modifications shown in Figs. 6 to 10 the mouthpiece 21 is formed as a screw threaded tube adapted to be screwed directly into the hole 4' of the tooth, the thread serving at the same time for the wing nut 31 arranged to press the suction pad 22 against the tooth. In Fig. 6 the said pad is shown to form one piece with the wing nut, while in Fig. 7 these members are shown to be separate.

According to Figs. 8, 9 and 8^a the application of the mouthpiece 21^b is again effected by directly screwing into the dental canal of the tooth 3. While the suction pad 22, in this case, is of a shape particularly adapted for use upon molar teeth, packing being carried out by a special pad 32 directly attached to the wing nut 31. Quite a similar arrangement is the one shown in Figs. 10, 10^a and 10^b the only difference being in the shape of the suction pad 22.

What I claim is:—

1. In a dental appliance for removing secretions from dental canals by suction through the drilled crown of the tooth, in combination a suction conduit and means to create a vacuum within said suction conduit, a mouthpiece in connection with said suction conduit and in airtight communication with the drill hole in said tooth, and a clamp to guide the said mouthpiece and comprising pivotal jaws adapted to bear with lateral pressure upon the crown.

2. In a dental appliance for removing secretions from dental canals by suction, through the drilled crown of the tooth, in combination a suction conduit and means to create a vacuum within said suction conduit, an externally threaded mouthpiece, a stirrup in which the said mouthpiece may be screwed up and down, a tubular extension to the mouthpiece turnable in an airtight ball socket joint at the end of same, a suction plate of packing material on said extension, hinged fixing jaws on the said stirrup, and screw to fix the jaws and the stirrup to the crown of the tooth by the application of lateral pressure.

3. In a dental appliance for removing secretions from dental canals by suction through the drilled crown of the tooth, in combination a suction conduit and means to create a vacuum within said suction conduit, a mouthpiece in connection with the said suction conduit and in airtight communication with the drill hole in the tooth, a clamp to guide the said mouthpiece, pivotal jaws pivoted to the said clamp, means to exert lateral pressure to the said jaws, and resilient pads on the jaws for contact with the crown of the tooth.

In witness whereof I affix my signature.

ROBERT FUST.
